LIQUID CIRCULATING HEATING SYSTEM

Laurance H. Gillick, Evanston, Timothy J. Lehane, North Riverside, and Norman O. Kirkby, Elmhurst, Ill., assignors to Vapor Heating Corporation, Chicago, Ill., a corporation of Delaware

Application August 4, 1949, Serial No. 108,574

11 Claims. (Cl. 237—5)

1

This invention relates to space heating systems and more particularly to heating systems of the above class comprising a primary heating apparatus and a secondary apparatus which cooperate, under predetermined conditions, to maintain the said space at a desired temperature.

One of the objects of the invention is to provide a heating system of the above general class in which the secondary heating apparatus includes a plurality of heat radiating units, each arranged for heating a particular zone of an enclosed space and each unit being independently thermostatically controlled in relation to the heating requirements of its associated zone.

Another object of the invention is to provide improved arrangements and constructions whereby a heated liquid is circulated by forced circulation through the secondary heating apparatus under certain operative conditions and during other conditions is circulated through said heating apparatus by gravity.

A further object of the invention is to provide, in a heating system utilizing relatively long heat radiating units, novel means for equalizing the temperature of heat radiated from the full length of said units and thereby avoid extreme differentials in temperature between the inlet and outlet end portions thereof.

Other objects and advantages of the invention will become apparent from the following description taken in connection with the accompanying drawings in which:

Fig. 1 is a diagrammatic plan view of a heating system in accordance with the invention, shown as applied to a railroad passenger car.

Fig. 2 is a longitudinal sectional view taken substantially on line 2—2 of Fig. 1.

Fig. 3 is a sectional view illustrating a spring opened solenoid valve for controlling the admission of heating medium to one of the smaller length radiators shown in Fig. 1.

Fig. 4 is a diagrammatic view, partly in section, of a by-pass valve associated with the liquid circulating system.

Fig. 5 is a side view, partially in section, illustrating a connection of the return end of a radiator connected with the inlet end thereof.

Fig. 6 is a diagrammatic view of a steam supply valve, hereafter referred to as a vapor regulator, which so regulates the delivery of steam to heat exchangers of the primary and secondary heating apparatus as to maintain the steam vapor therein at substantially atmospheric pressure.

Fig. 7 is a wiring diagram of the electrical circuits for controlling the operations of the several

elements of the primary and secondary heating apparatus.

Referring to the drawings, the invention, for purposes of illustration, is shown as applied to a railroad passenger car, indicated diagrammatically in Figs. 1 and 2. It is to be understood, however, that the invention is not to be limited in its use to the particular application described, but may be used to heat any enclosure where steam is available as a primary source of heat. The heating system, as herein illustrated, comprises a primary heating apparatus which is effective to deliver heat into the interior of the car, herein exemplifying any enclosed space, whenever heat is required, and a secondary heating apparatus which is effective to supply additional heat to various zones of the enclosed space when such additional heat is required.

PRIMARY HEATING APPARATUS

The primary heating apparatus includes an air heater A, located in an air duct B, and a blower C for forcing a stream of air through the heater A; the heated air being delivered into the upper portion of the enclosed space, for example a railway car, through discharge ports D formed in the air duct B. The air heater A, in the present disclosure, utilizes steam as a heating medium. The steam flows from a source of supply, for example, steam train line E, through a vapor regulator F and a pipe G to a solenoid admission valve H interposed in the pipe G. The said admission valve H is normally closed by a spring I and is opened by the energization of the solenoid J. The solenoid, as will be hereinafter described, is controlled by temperature responsive means including a primary heat thermostat K which is responsive to the general temperature of the car as a whole. For example, when the general temperature of the car falls below the functional setting of thermostat K, the valve H is opened to admit steam into the air heater A. Condensation from the steam is discharged through a pipe L to drain pipe M of the pressure regulator F.

SECONDARY HEATING APPARATUS

General function

The secondary heating apparatus cooperates with the primary heating apparatus to supply heat to the car in the amounts suitable to meet the heating requirements of the several zones thereof which may differ in regard to their heating requirements. This apparatus utilizes a heated liquid as a heating medium; the liquid being circulated through separate radiators located

in the several zones. The said liquid is heated in a heat exchanger 10 which receives its source of heat from the steam train line E. The steam passes from the steam train line E at relatively high pressure through a shut-off valve 11 in pipe 12 and into the vapor regulator F; which regulator functions to deliver the steam at substantially atmospheric pressure to the heat exchanger 10. The low pressure steam passing from the vapor regulator F to the heat exchanger 10 through pipe 14 and the condensation and surplus steam is discharged through return pipe 15 to the drain outlet 16.

VAPOR REGULATOR

The vapor regulator F is illustrated diagrammatically in Fig. 6, since the specific structures thereof are not required for a thorough understanding of the present invention. It will be sufficient, therefore, to confine the description of the said regulator to its control functions. These control functions are as follows. The steam from the train line E enters chamber 15a and passes through valved port 16a into chamber 17. When the steam in chamber 17 reaches a predetermined low pressure, the pressure actuated valve 18 is closed to a position to maintain the desired pressure in said chamber 17. When steam is required in the heat exchanger 10, the steam passes through a valve controlled port 19 into a low pressure chamber 20 from which it is delivered through pipe 14 into the heat exchanger 10. When the heat exchanger is filled with steam, any surplus passes out through the return pipe 15 to the drain outlet 16. The condensation is discharged through the drain outlet, but the steam flows upwardly into a thermostat chamber 21 of the vapor regulator and applies heat to a bellows form of thermostat 22. The expansion of the bellows thermostat rocks a lever 23 and thereby closes a spring opened valve 24 to close port 19 and thereby shuts off the delivery of steam to the heat exchanger. Inasmuch as the outlet pipe 15 and thermostat chamber 21 are open to the atmosphere, the steam pressure in the heat exchanger will be maintained at substantially atmospheric pressure.

The supply of steam to the heat exchanger can also be shut off by opening a valve 25 and thereby permit steam to pass direct from the chamber 20 into the thermostat chamber 21. This valve will open, in the event that the pressure in chamber 20 exceeds a predetermined value, by compressing the spring 26 which normally holds the valve 25 closed. Also the valve 25 may be opened by the energization of solenoid N. This solenoid is therefore controlled by the conjoint actions of the control means of both the primary heating apparatus and the secondary heating apparatus, as will be hereinafter described, so that steam will be supplied to the heat exchanger 10 only when the primary heating apparatus is delivering heat into the enclosed space and at least one of the several secondary heat thermostats hereinafter mentioned is calling for heat.

SECONDARY HEATING APPARATUS

Zone heating

The enclosed space, herein exemplified as the interior of a railway car, is divided into several zones designated O, P, Q, R, S, T. The zones O, P, Q and R are served by radiators designated, respectively, in Figs. 1 and 2 by numerals 27, 28, 29 and 30, but the zones S and T are served by a single radiator 31 which is substantially longer

than the others. The radiator 28 is also relatively long since it extends the full length of the passenger space, of which zone P represents one side of the car. The shorter radiators 27, 29 and 30 are utilized to heat smaller zones, but inasmuch as these zones are located at the ends of the car and ordinarily have greater heat loss, the radiators are provided with a larger number of heat dissipating fins, per linear foot, than the radiators 28 and 31.

The liquid heating medium is delivered to the several radiators by means of a main circulating loop which may be located between the main and sub-flooring of the car and comprise a supply conduit 32 and a return conduit 33. A pressure responsive valve 34 connects the remote end of supply conduit 32 with the entrance end of the return conduit 33. Consequently, the liquid heating medium may circulate continuously through the main loop when the pressure therein is sufficient to unseat the pressure opened valve 34.

Connected in said main loop, in series with conduits 32 and 33, is a motor-driven pump 35 and connected in parallel with said pump is a by-pass 36 which operates to permit the system to function by gravity circulation when the motor of pump 35 is de-energized, for example, during lay-over periods when it is desired to maintain a lower temperature in the car.

Referring to Fig. 4, the by-pass includes a chamber 37 having ports 38 and 39 connected by conduits 40 and 41, respectively, to the return conduit 33. A spring biased valve 42 is contained in the chamber 37 and is normally retained in the position shown by the dotted lines, but under certain conditions of operation is caused to close the port 39 as will be hereinafter explained.

It will be observed that the inlet end of each radiator 27, 28, 29, 30 and 31 is provided, respectively, with separate solenoid admission valves 43, 44, 45, 46 and 47. The solenoid valve 43 for radiator 27, shown in Fig. 3, is connected by branch pipe 48 to the flow conduit 32 of the circulating loop and outlet end of the said radiator is connected by pipe 49 to the return conduit 33 of said circulating loop.

Considering said valve 43 as representative of the valves for the shorter radiators, it is shown in Fig. 3. It is normally held in its open position by means of a spring 50 so that the heated liquid will flow from the flow conduit 32, through pipe 48, admission valve 43, when the pump 34 is operating. When the pump is not operating, the liquid, when it is heated, will flow by gravity through the radiator 27 in the same direction as above described, but it will by-pass the pump 35. During this gravity circulation, the spring operated valve 42 assumes the full line position, shown in Fig. 4, so that the liquid will flow through the by-pass from the return conduit 33 at the suction side of the pump 35 through pipe 41, valve chamber 31, and pipe 40 to the conduit 33 at the pressure side of the pump.

Considering next the radiator 28, which is representative of the longer radiator units, the said unit 28 is provided with a fitting, indicated generally by the numeral 51, cooperating with said solenoid valve 44 and is connected to the flow conduit 32 of the circulating loop by conduit 53. The outlet end of the radiator unit 28 is connected to the return conduit 33 of said circulating loop by conduit 54.

The fitting 51 and solenoid valve 44 are shown

diagrammatically in detail in Fig. 5. The said fitting includes a housing in which is contained a nozzle 52 having a narrowing passageway, the discharge end of the nozzle being directed into the upper run of the radiator unit 28 and projecting beyond the mouth of a port opening 55 provided in the wall of the housing. A conduit 56 connects the port opening 55 with the outlet end of the radiator 28 which also connects into the return conduit 54.

The function of the fitting 51 is to equalize the temperature of the heating medium flowing through the relatively long radiator unit, so as to avoid extreme differentials in temperature between the inlet and outlet end portions of the radiator. It is known that in radiators composed of long conduits, gradations in temperature decrease progressively throughout the length of the conduit. This condition is remedied by the use of the fitting 51 which functions in the manner of an injector, as will be presently explained.

As the heating medium is caused to flow through the narrowing passageway of the nozzle 52 into the inlet end of the radiator 28, its velocity of flow entrains from the connecting conduit 56, a portion of the liquid from the discharge end of the radiator and recirculates the entrained liquid through the radiator. Thus, the heating medium entering the radiating unit at a relatively higher temperature is intermixed with the spent medium entrained from the discharge end of the radiator, thereby reducing the temperature of the heating medium introduced, but by recirculating a portion of the spent medium maintains greater uniformity in heat radiation throughout the full length of the radiator and therefore increases its heating efficiency as a whole.

The radiator units 29 and 30 are connected in the supply and return conduits 32 and 33 of the circulating loop in substantially the same manner as described in connection with radiator 27; the inlet and outlet of radiator 29 being connected into the loop by branches 57, 58 and radiator 30 being connected into said loop by branches 59 and 60. The long radiator 31 is similar to the radiator 28 and is provided with a fitting 51^a which corresponds in structure to fitting 51 and is connected into the circulating loop by branch conduits 61 and 62. Each conduit leading from the flow conduit 32 of the circulating loop to a radiator admission valve is provided with an orifice fitting 63. The orifice passages of the said fittings are so proportioned, having regard to the friction, location and heating requirements of the several radiators, to balance the distribution of heating medium among the several radiators. Also all admission valves are normally open as described in connection with valve 43, whereby it is necessary to energize their associated solenoids 124, 124^a, 124^b, 124^c, and 124^d, to close said valves.

The primary heating apparatus, as before indicated, is responsive to the general temperature of the car or space being heated. The secondary heating apparatus delivers heat into the several zones of the car, but it is dependent for its operation upon the condition of the controls of the primary heating apparatus, since the primary apparatus must be in operating condition before any part of the secondary apparatus.

The operation of the improved heating system will best be understood by reference to Fig. 7 of the drawings which show the electrical wiring diagram thereof.

CONTROL CIRCUITS

Primary apparatus

Considering first, the electrical circuits for opening the steam valve H to deliver steam to the air heater A of the primary apparatus: These circuits are closed through a main relay 64 under the control of said primary heat thermostat K. The said thermostat is provided with an electrical auxiliary heater 65 which, for the purpose of establishing its functional setting, receives electrical heating current through a circuit leading from positive line 66 through wire 67, variable resistor 68, fixed resistor 69, wire 70, auxiliary heater 65, and wire 71 to the negative line 72. The setting of the variable resistor 68, shown in Fig. 7, may be regarded, for purpose of illustration, as establishing the functional setting of thermostat K at 76° F. This temperature setting may be raised or lowered by appropriate adjustment of the variable resistor 68.

When the thermostat K calls for heat, the relay 64 is energized to close, through its contact 80, a circuit for energizing the solenoid J of steam valve H and thereby deliver steam to the air heater A. The circuit for energizing said relay 64 leads from positive line 66 through wire 73, resistor 74, relay solenoid 75, wire 76, resistor 77 and wire 78 to the negative line 72. The closing of said relay establishes the said energizing circuit for the steam valve solenoid J, which circuit is as follows: Positive line 66, wire 79, closed relay contact 80, wire 81, solenoid J of steam valve H and wire 82 to negative line 72.

Simultaneously with the energization of the said circuit for opening the steam valve H, a circuit is closed through energized contact 83 of relay 64 to establish a circuit for applying additional heating current to auxiliary heater 65. This additional circuit leads from positive line 66 through wire 84, relay contact 83, cycle resistor 85, having a heat control value of 2° F., and wires 86 and 70 through the heater 65 and said wire 71 to the negative line 72. The 2° of heat added to the thermostat K as a result of the last mentioned circuit reduces the temperature setting of thermostat K to 74° F. until its mercury column 87 engages its contact 72. This functioning of the thermostat K results in de-energizing the relay 64, since, under such conditions, the electric current is by-passed around the relay solenoid 75. This by-passing circuit leads from the positive side of the solenoid 75 through wire 88, contact 89 of thermostat K and through its mercury column 87 to wire 90 and wire 76, resistor 77 and wire 78 to the negative line 72. The said deenergization of relay 64 opens relay contact 83 and therefore removes the 2° of heat from the auxiliary heater 65 of thermostat K. The auxiliary heater therefore cools and again opens the thermostat at its contact 89 and again results in reenergizing the solenoid 75 of relay 64. This cycling operation will continue, and momentary bursts of steam will be delivered to the air heater A, until the temperature of the enclosed space being heated is sufficient to maintain the thermostat K closed.

CONTROL CIRCUITS

Secondary apparatus

Referring now to the circuits for controlling the operations of the several radiators of the secondary heating apparatus: The radiators 27, 28 and 29 located in zones O, P and Q at one side

of the car, are controlled by their individual thermostats 91, 92 and 93, provided with electrical heaters 94, 95 and 96. The radiators 30 and 31 are controlled by thermostats 97 and 98 provided with electrical heaters 99 and 100. The several 5 thermostats just described are secondary heat thermostats and are set to function at the same temperature as the primary heat thermostat K, for example 76° F., and the auxiliary heaters of the said thermostats have the same heat control 10 value (2° F.) as the electrical heater 65 of the primary heat thermostat K.

Dependence of secondary apparatus

The secondary heat thermostats 91, 92, 93, 97 and 98 may function to shut off the delivery of steam to their respective radiators, but heating medium will be delivered to said radiators only when the primary heat thermostat K is calling for heat. In other words, the secondary apparatus is dependent upon the condition of the controls of the primary apparatus. This dependence is obtained by utilizing the conjoint functions of the primary heat thermostat K and the secondary heat thermostats 91, 92, 93, 97 and 98 to control the delivery of steam to the liquid heater 10. This result is obtained by controlling the energization of solenoid N of spring closed valve 25 of the vapor regulator F. Consequently, the energizing circuit for the said solenoid N is 30 connected in series through a group of relays 101, 102, 103, 104 and 105; the said relays being connected in parallel through the main relay 64, the latter of which is controlled by primary heat thermostat K. Consequently, when the primary 35 heat thermostat K is calling for heat, the solenoid N of valve 25 will be deenergized to shut off the direct passage of steam from chamber 20 to the thermal chamber 21 of the vapor regulator F and thereby permit the steam to pass from chamber 20 of the vapor regulator into the heat exchanger 10, provided, of course, that at least one of the secondary thermostats is calling for heat.

The energizing circuit for said solenoid N for opening valve 25 leads from the positive line 66 through conductor 106 which is connected in series through the top contacts 107, 108, 109, 110 and 111, of the said relays 101, 102, 103, 104 and 105, respectively, and thence through the solenoid N and wire 112 to the negative line. The actuating solenoids of the last mentioned group of relays are energized by circuits closed by the energized relay 64. Considering first the circuit for energizing the actuating solenoid of relay 101: The circuit leads from positive line 66 through bus connector 113, energized closed contact 114 of relay 64, wire 115, resistor 116, wire 117, solenoid coil 118 of relay 101, wire 119, resistor 120 and wire 121 to the negative line. The energization of said relay solenoid 118, in addition to being controlled by the energization of the main relay 64, is also controlled by the functioning of the secondary heat thermostat 91 to by-pass the electric current around solenoid 118. This by-pass connection includes wire 122 leading from wire 117, at the positive side of solenoid 118, to the upper contact of thermostat 91 and wire 123 which leads from the lower contact of thermostat 91 to the wire 119 at the negative side of solenoid 118. Consequently, when the temperature of the zone O, served by radiator 27, is sufficient to cause secondary heat thermostat 91 to function, the electric current is bypassed around solenoid 118 of relay 101 and per-

mits this relay to close, as is indicated in the drawing, and therefore energizes the solenoid 124 of the radiator valve 43 to close the said valve against the compression of spring 50. The valve 43 will be held closed until the temperature of zone O is lowered by loss of heat therefrom or until the electric heater 94 is deenergized to remove the electrical heat (2°) from the thermostat.

The secondary heat thermostat 91 will function when the temperature in zone O, in which the thermostat is located, reaches the adjusted functional setting of the thermostat, for example 74° F., but the thermostat heater 94 will retain its heat until the primary heat thermostat K reaches its adjusted functional setting of 74° F. This condition is due to the fact that the heater 94 is connected through contact 125, relay 64, cycle resistor 127, wire 128, heater 94, wires 129 and 121 to the negative line 72. Consequently the secondary heat thermostat 91 will cycle, by removal and re-application of auxiliary heat thereto, during the cycling operation of the primary heat thermostat K. Under such conditions, 25 the secondary heat thermostat 91 will cycle to deliver small quantities of heating medium to radiator 27 until the temperature of said zone O reaches the normal setting (76° F.) of the said thermostat 91.

The radiators 28, 29, 30 and 31, as before indicated, are controlled in the same manner as said radiator 27, by means of the secondary heat thermostats 92, 93, 97 and 98, through their associated relays 102, 103, 104 and 105. Inasmuch as the energizing circuits for the solenoids 118^a, 118^b, 118^c, and 118^d for the relays 102, 103, 104 and 105, respectively, are energized through contacts 114^a, 114^b, 114^c, and 114^d of relay 64 in the same manner and simultaneously with the solenoid 114 of relay 101, these several circuits are identified by the same numerals as the energizing circuit of solenoid 118 with the addition of exponents a, b, c and d. The energizing circuits for the solenoids 124^a, 124^b, 124^c, and 124^d for the admission valves 44, 45, 46 and 47 for the radiators 28, 29, 30 and 31 and the by-passing circuits for deenergizing said solenoids are substantially the same as corresponding portions of the circuits associated with relay 101 and secondary heat thermostat 91. Therefore in order to avoid repetition of description the several circuits are identified by the same reference numerals as the corresponding circuit associated with relay 101 and thermostat 91, with the addition of the exponents a, b, c and d.

The pump 35 is controlled by a relay 130 and is operative on an independent circuit. The relay 130 is normally energized to maintain the contact bar 131 out of engagement with the contact points 132 and 133. When there is a requirement for heat in any one of the zones, as was hereinbefore explained, any of the relays such as 101, 102, 103, 104 or 105 in becoming energized, will effect separation from the contacts from the respective contact bars to open the circuit through the various relays to deenergize the relay 130 which causes the contact bar 131 to engage contacts 132 and 133 to effect operation of the pump 35. The blower C is connected to the line 66 and 72 through conductors 134 and 135 through switch 136.

The operation of the by-pass 36 will be understood by referring to Fig. 4. As heating medium is pumped by the pump 35 in the direction of 75 the arrows, the pressure created in the conduits

33 and 40 causes the valve flap 42 to seat against the port opening of pipe 41 to prevent recirculation of the medium through conduit 41. However, when the car is out of service for any extended period of time and it is desired to maintain heat in the car without burdening the battery system thereof, the valve flap 42 is caused by its spring to open, permitting heating medium to flow by gravity through conduit 41 through the chamber 37, through the conduit 40 into conduit 33 thereby by-passing the pump 35 which would normally prevent such movement of heating medium.

We claim:

1. A heating system comprising a primary heating apparatus and a secondary heating apparatus, each including a heat radiating unit and an electrical valve for controlling the admission of heating medium thereto, means including a primary heat thermostat and a secondary heat thermostat and separate relays associated therewith for controlling the operation of said valves, the relay for controlling the secondary apparatus being energized by a circuit connected through the relay associated with the primary heat thermostat and the secondary thermostat being interposed in a by-pass circuit connected in the energizing circuit of its associated relay, whereby the functioning of either thermostat while the other is calling for heat is effective to deenergize the relay associated with said secondary heat thermostat.

2. A heating system comprising a primary heating apparatus including a heat radiating unit and a solenoid valve for controlling the admission of heating medium thereto, a secondary heating apparatus including a heat radiating unit delivery of heating medium thereto, means in and a solenoid valve for controlling the delivery of heating medium thereto, means including a primary of heating medium thereto, means including a heat thermostat and a relay switch associated therewith for controlling the energization of the solenoid valve associated with the primary heating apparatus, means including a secondary heat thermostat and a relay switch associated therewith and electrically connected through the first mentioned relay switch, whereby the secondary heating apparatus can be effective only when the primary apparatus is operative and the secondary heat thermostat associated with the last mentioned relay is calling for heat.

3. A heating system comprising a primary heating apparatus and secondary heating apparatus, each including a heat radiating unit in which a heating medium is adapted to circulate, a heat exchanger having its source of heat derived from a steam line and adapted for heating a liquid medium adapted for circulating in said secondary heating apparatus, means including a primary heat thermostat associated with said primary heating apparatus for controlling the flow of heating medium thereto in response to the action of said primary heat thermostat, and means associated with said secondary heating apparatus and with said first mentioned means and adapted to cause the flow of heating medium through said secondary heating apparatus only when said primary heating apparatus is operative.

4. A heating system comprising a primary heating apparatus including a radiating unit in which steam is used as a heating medium, and a secondary heating apparatus including a radi-

ating unit in which a heated liquid is adapted to circulate, a primary heat thermostat associated with the primary heating apparatus, a secondary heat thermostat associated with the secondary heating apparatus, means associated with said primary heating apparatus adapted to cause the flow of steam therethrough in response to the action of its associated thermostat, means associated with said secondary heating apparatus and with said first mentioned means and adapted to cause the flow of heating medium through said secondary heating apparatus only when said primary heating apparatus is operative.

5. A heating system comprising a primary heating apparatus including a heat radiating unit in which a heating medium is adapted to circulate, a primary heat thermostat associated with said primary heating apparatus, a relay switch in electrical connection with said primary heat thermostat, a solenoid valve associated with said radiating unit for controlling the flow of said heating medium therethrough, said solenoid valve being in electrical connection with said relay, a heat exchanger adapted for heating a liquid medium, a conduit loop connected to said heat exchanger, pump means for circulating said medium through said conduit loop, a plurality of secondary heating elements each of which is connected into said loop, a separate secondary heat thermostat associated with each of said secondary heating elements, a separate relay switch in electrical connection with each of said secondary heat thermostats and said first mentioned relay switch, a solenoid valve associated with each of said heating elements, each of said solenoid valves being in electrical contact with corresponding relays, whereby each of said secondary heating elements are independently operable but only when said primary apparatus is in operation.

6. A heating system comprising a primary heating apparatus including a heat radiating unit in which a heating medium is adapted to circulate, a thermostat associated with said primary apparatus, a relay switch in electrical connection with said thermostat, a solenoid valve associated with said radiating unit for controlling the flow of said heating medium therethrough, said solenoid valve being in electrical connection with said relay, a heat exchanger adapted for heating a liquid medium, means for supplying steam thereto, a secondary heating apparatus including a radiating unit connected to said heat exchanger, pump means for circulating heating medium through said radiating unit, a thermostat associated with said secondary apparatus, a relay switch in electrical connection with said thermostat associated with the secondary apparatus and with said first mentioned relay switch, a solenoid valve associated with said radiating unit for controlling the flow of said heating medium therethrough, said solenoid valve being in electrical connection with said relay, means including a solenoid valve effective when energized to shut off the delivery of steam to said heat exchanger, and means defining an energizing circuit for the last mentioned solenoid valve connected through the relay associated with the secondary heating apparatus, whereby steam is delivered to said heat exchanger only when both said thermostats are calling for heat.

7. A heating system as defined in claim 5 having means for by-passing heating medium around the pump means so as to permit circulation of said medium by gravity.

11

8. A heating system as defined in claim 5 in which the heating medium in the primary heating apparatus is steam and which includes thermostatically controlled means for regulating the pressure of the steam entering into the heat exchanger.

9. A heating system as defined in claim 5 having means associated with a radiating unit of the secondary heating apparatus for recirculating in intermixed relation a portion of spent heating medium leaving said unit with fresh heating medium entering into said unit to equalize the temperature throughout the full length of said unit.

10. A heating system according to claim 6 in which the secondary heating apparatus includes a plurality of separate radiating units, a solenoid admission valve for each unit, separate control thermostats and solenoid switches associated therewith, and in which the solenoid valve for controlling the delivery of steam to the said heat exchanger is connected in series through each of the relay switches associated with the several radiating units of the secondary apparatus, whereby steam is supplied to the heat exchanger when the primary heating apparatus and any one of the radiating units of the secondary apparatus is effective.

11. A heating system according to claim 6 in

12

which the secondary heating apparatus includes a plurality of separate radiating units, a solenoid admission valve for each unit, separate control thermostats and solenoid switches associated therewith and connected in parallel through the solenoid switch associated with the primary heating apparatus, and in which the solenoid valve for controlling the delivery of steam to the said heat exchanger is connected in series through each of the relay switches associated with the several radiating units of the secondary apparatus, whereby steam is supplied to the heat exchanger when the primary heating apparatus and any one of the radiating units of the secondary apparatus is effective.
